US00D996456S

(12) **United States Design Patent** (10) Patent No.: **US D996,456 S**
(45) Date of Patent: **** Aug. 22, 2023**

(54) **DISPLAY SCREEN OR PORTION THEREOF WITH GRAPHICAL USER INTERFACE**

(71) Applicant: **Lutron Technology Company LLC**, Coopersburg, PA (US)

(72) Inventors: **Manisha Dahiya Baluja**, Lansdale, PA (US); **John N. Callen**, Center Valley, PA (US); **Duheng Liang**, Bethlehem, PA (US); **Shenchi Tian**, Easton, PA (US)

(73) Assignee: **Lutron Technology Company LLC**, Coopersburg, PA (US)

(**) Term: **15 Years**

(21) Appl. No.: **29/832,074**

(22) Filed: **Mar. 24, 2022**

Related U.S. Application Data

(63) Continuation of application No. 29/749,201, filed on Sep. 3, 2020, now Pat. No. Des. 950,577, which is a continuation of application No. 29/660,144, filed on Aug. 17, 2018, now Pat. No. Des. 898,041, which is a continuation of application No. 29/590,902, filed on Jan. 13, 2017, now abandoned.

CLAIM

The ornamental design for a display screen or portion thereof with graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 shows a display screen or portion thereof with graphical user interface showing our new design; and, FIG. 2 shows a second embodiment thereof.

The peripheral dashed broken lines illustrate a display screen or portion thereof, and form no part of the claimed design.

**1 Claim, 1 Drawing Sheet
(1 of 1 Drawing Sheet(s) Filed in Color)**
